The ornamental design for an electric gripper, as shown and described.

DESCRIPTION

FIG. 1 is a front perspective view of an electric gripper showing our new design;

FIG. 2 is a rear perspective view thereof;

FIG. 3 is a front elevational view thereof;

FIG. 4 is rear elevational view thereof;

FIG. 5 is a left-side elevational view thereof;

FIG. 6 is a right-side elevational view thereof;

FIG. 7 is a top plan view thereof;

FIG. 8 is bottom plan view thereof;

FIG. 9 is an enlarged detail view of portion 9 in FIG. 1 thereof; and,

FIG. 10 is an enlarged detail view of portion 10 in FIG. 2. The evenly dashed broken lines depict portions of the electric gripper that form no part of the claimed design. The dot-dash boundary lines define the boundary of the claimed design and form no part of the claimed design. The dot-dash broken lines shown in enlarged detail portion views FIGS. 9-10 indicate cutoff boundaries and form no part of the claim.
